UNITED STATES PATENT OFFICE.

WILLIAM S. MILLS, OF TRUMBULL, CONNECTICUT.

WORK-FEEDING ATTACHMENT FOR SEWING-MACHINES.

1,119,099.

Specification of Letters Patent.

Patented Dec. 1, 1914.

Application filed August 21, 1912. Serial No. 716,194.

To all whom it may concern:

Be it known that I, WILLIAM S. MILLS, citizen of the United States, and resident of Trumbull, in the county of Fairfield and State of Connecticut, have invented certain new and useful Improvements in Work-Feeding Attachments for Sewing-Machines, of which the following is a specification.

My present invention relates to improvements in feeding attachments for sewing machines, and belongs to that type of attachment shown and described in my prior Patent #552,691, for feeding work to the needle of a sewing machine.

The invention is especially fitted for stitching fabric labels on shirts and other garments, or in fact in stitching pieces of material of predetermined shapes and sizes upon apparel of various sorts. The nature of my invention is such as to enable me to stitch on labels of the above class without turning the work while in the machine and by simply moving the work forward, backward and longitudinally of the sewing machine bed in a way to follow and stitch down the outer edges of the label.

This invention relates more particularly to improved mechanism for receiving and holding the label to be stitched, in proper position to be guided backward, forward and crosswise with relation to the operating needle; to include in said construction a special shaped presser foot that is designed to normally hold the label down firmly upon the cloth to which it is to be attached while the needle is working around the outer edges of the said presser foot; to support this presser foot from the movable part of the attachment while guiding the work over the bed of the machine and with relation to the needle; to provide means for shifting the relative position of the support for the presser foot so as to operate entirely around the presser foot without interfering with said supporting means, and finally to provide means whereby the said presser foot and its supporting means may be raised and lowered for the introduction and removal of the work.

With these and other objects in view the invention further resides and consists in the construction and novel combination and arrangement of parts hereinafter more fully described, illustrated in the accompanying drawings, and pointed out in the claims

hereto appended, it being understood that various changes in the form, proportion, size and minor details of construction within the scope of the claims may be resorted to without departure from the spirit or sacrificing any of the advantages of the invention.

Suitable numerals of reference will be found to denote like or corresponding parts throughout the several figures of the accompanying drawings forming a part of this specification and upon which,

Figure 1, shows a side elevation of the work feeding attachment applied to a sewing machine head, the needle bar being illustrated in a raised position and adapted to operate in connection with my improved work feeding attachment. Fig. 2, is a plan view of my improved work feeding attachment as it would appear when secured to the bed of a sewing machine, in position for beginning an operation, and corresponding with Fig. 1. Fig. 3, is a slightly enlarged end view of the presser foot and attached parts of my improved work feeding attachment, as seen from arrow *a*, Fig. 1. Fig. 4, is a further enlarged end view of the presser foot and attached parts of the work feeding attachment, shown in Figs. 1, 2 and 3, but the supporting arm for the presser foot being in a different position. Fig. 5, is an enlarged cross sectional view of the attachment taken on line 5—5 of Fig. 2, the position of the parts corresponding with Figs. 2 and 3. Fig. 6, is also an enlarged cross section somewhat like Fig. 5, but with parts in position shown in Figs. 4 and 7. Fig. 7, is an enlarged plan view somewhat like Fig. 2, but with supporting shaft and pin for presser foot in a different position to agree with Figs. 4 and 6, and, Fig. 8, shows a separate plan view of a label such as my attachment is designed to stitch on to a garment.

I have illustrated that portion of my former patented device herein, which includes the means for moving the work supporting plates and presser foot in backward, forward and longitudinal directions with respect to the bed of the sewing machine head and the needle hole therethrough.

For the purpose of more clearly understanding the said mechanism, I will now briefly refer to the parts by reference numerals, wherein—

8 represents the bed of a sewing machine

head, and 9 the usual needle hole therein. The needle 10 is carried in a reciprocating needle bar 11 operatively mounted in the head (not shown) of the machine. I have also herein omitted the other immaterial operative parts of the sewing machine head, such as the shuttle carriage and connections.

A bracket 12 is secured to the bed of the machine head by screws 13 to support the operating shaft 14. On the upper end of this shaft is mounted an operating handle 15 so it may be rotated by hand, step by step, during the operation of the sewing machine. A small pinion 16 is mounted upon this shaft (see dotted lines Fig. 2) in position to engage the racks 17 that are secured to the longitudinally reciprocating slide 18. This slide, as will be noted, is in turn mounted in a lower slide 19 which is free to be moved in a forward and backward direction or at a right angle to the movement of the first named slide. It will be apparent that an operation of the shaft 14 will give to the slide 18 and its supported parts a forward and backward movement and a movement lengthwise of the bed of the sewing machine head, and that said movements when combined produce a corresponding rectangular movement of the work supporting parts and presser foot.

A work supporting plate 20 is secured to a bracket 21 attached to the slide 18 and is moved backward and forward upon the top of the bed of the sewing machine with the several movements of the said slide. This plate is provided with a rectangular opening 22, as shown in Figs. 2 and 7, and is the same size as the opening 23 in the clamping plate 24. The said plate 20 serves to support the garment to which the label 30 is fastened, while the clamping plate 24 arranged above the guide plate serves to close down on the top of the garment and clamp it against the bottom plate 20. This clamping plate 24 is secured between the outer ends of the two parallel side members 25 whose inner portions are connected by a cross piece 26, the said ends of the side members 25 are pivotally connected to the outwardly disposed end of the before mentioned bracket 21. A yoke 26^a is secured to the intermediate portion of the side members 25 to serve as a bearing for a spring 27 which is adjustably secured to the upwardly disposed bracket 28 secured to the before mentioned slide 18. The purpose of this spring and its connections are to force the said yoke, its frame and clamping plate 24 downward, whereby the garment will be firmly held beneath the clamping plate and against the work supporting plate 20. The side frame members 25 carrying the clamping plate are pivoted to the ends of the bracket 21 so that the plate may be raised and lowered against the action of the spring

27 for the placement or removal of the garment to which the label is to be attached. These work supporting parts may be raised at the completion of a stitching operation for the removal of the label by the manipulation of the links 29 attached to the before mentioned yoke 26.

The label 30, shown in Fig. 8, may be formed of cotton, linen or other suitable material, and is stitched to any form of garment, either woven or knitted, after the same has been placed upon the supporting plate 20, adjusted to the position desired, and then clamped by the plate 24 which is lowered upon it. The labels are formed of a shape and size to correspond with the opening 23 in the clamping plate and after being placed therein and upon the garment, the presser foot 31 is lowered to hold the label in position during the stitching operations. The presser foot covers the central portion of the label only and leaves a space between it and the edge of the opening 23 of the clamping plate so that the needle will be free to operate upon the upper top edge portion of the label for its attachment to the garment supported beneath it. The presser foot is mounted to be raised and lowered to permit the insertion and engagement of the label, and is also provided with means for clamping the label down upon the garment comprising in part a hinged plate 32 which is pivotally connected to a pin 33 in a forwardly extended portion of the before mentioned slide 18. Upon this hinged plate is mounted a guide bracket 34 having two upwardly disposed bearings 35 thereon. A rocker shaft 36 is mounted in these two bearings and is provided with collars 37 and 38 fitted against the said bearings. The latter one 38 of said collars is provided with two flat surfaces 38^a that are engaged by a spring 39 secured to the top of one of the said bearings 35 to yieldably hold the shaft in either of two positions. On the outer end of this rocker shaft is supported a disk 40 carrying an eccentric pin 41 the outer end of which engages a disk 42 mounted to rotate in a pocket of the presser foot. This disk is also provided with two flat peripheral surfaces that are engaged by a spring 43 to yieldably hold the shaft and disks in either of two positions. A spring 44 is adjustably connected to the before mentioned bracket 28 and extends forward so that its free end engages the bearing 35 of bracket 34 in a way to hold the same, the hinged plate, rocker shaft and presser foot, down to clamp the latter against the label and hold it in position while stitching. The presser foot is raised with the completion of each label stitching operation by manipulating the link 45 and lever 46 to lift the same against the action of its spring 44.

The connecting pin 41 carried by the disk 130

40 is mounted off center and likewise operatively engages the disk 42 in the presser foot, off center, so that when the rocker shaft 36 is turned the pin 41 is thrown 5 around the axis of the shaft and disks in a manner to turn the disk 42 and thus move the pin connection with the presser foot, to a different position, and toward the opposite end of the presser foot, in a way to 10 leave the position of presser foot the same with regard to the openings in the supporting and clamping plates.

The shafts and disks are normally set for the beginning of an operation in the position shown in Figs. 2, 3 and 5 which leaves 15 the supporting pin 41 for presser foot, to the rear of the needle hole 9 thereby permitting the needle to work forward between the presser foot and edge of opening 23 20 in plate 24 while the presser foot together with the work supporting guide plate and clamping plate are moved toward the operator. This movement is continued until the rear right hand corner of the label is 25 reached, whereupon the label and its supporting parts are moved to the right thereby producing the cross stitches along the rear edge portion of the label, bringing the parts to the other rear corner. A continued 30 operation of the machine carries the work directly rearward, then across, and forward again to the point of beginning, as shown in Fig. 7, thus having guided the entire edge portion of the label around the operating needle in a rectangular manner. The 35 under face of the presser foot is preferably notched as shown in Fig. 3, to better engage the label and clamp it in position upon the garment during the stitching operation.

40 During the operation of the sewing machine and this forward movement of the slide plate 32, shaft 36 and its supporting pin 41 the arm 47 upon the shaft 36, which is normally disposed forward as shown in 45 Figs. 2 and 5, is brought to engage the screw 48 mounted in a lug 49 secured to the bed of the machine. This screw thus serves to shove the arm back in a way to hold said shaft 36, see Fig. 6, causing the said shaft 50 to be rocked while the sewing machine is in operation.

From the foregoing it will be noted that the presser foot is supported upon the pin of the shaft and remains in a fixed position 55 with relation to said pin until the shaft is operated, when the pin is moved and its location shifted with regard to the plate and presser foot. This, of course, necessarily means that the presser foot and guide plate 60 at all times remain in positions corresponding to each other and that the pin only is moved with relation to them. The shaft and pin are set in the position shown in Figs. 2 and 3 for the beginning of an operation and remain in that position until the

parts move toward the operator sufficient for the engagement of the arm 47 with the adjustable stop screw 48 mounted in the lug 49 secured to the bed of the sewing machine head. This engagement of the arm 70 with the screw necessarily throws the arm and shaft, while the guide plate and other parts continue to move forward with relation to the said arm and screw. This operation throws the pin and operates the disks 75 in a way to shift the relative position of the said pin, so as to be connected with the rear portion of the presser foot, as shown in Figs. 4, 6 and 7, instead of the front portion, as shown in Figs. 2 and 3. It will thus 80 be obvious that when the parts continue to move around and the needle works up to the finishing point, the pin will still be in said relatively rear position and is sufficiently out of the way to permit the needle 85 to finish up against the beginning end of the row of stitches.

Having thus described my invention what I claim and desire to secure by Letters Patent is:—

1. A work feeding attachment for sewing machines, comprising slidable work supporting plates one of which has an opening therein, a presser foot arranged central in the opening to engage the work and adapted to 90 be moved with said plates, a rocker shaft for supporting the presser foot, movable connections between the rocker shaft and presser foot, means for rotating the rocker shaft and shifting the relative location of the connections of the shaft with the presser foot 95 and longitudinally of said presser foot while the sewing machine is in operation.

2. A work feeding attachment for sewing machines, comprising slidable work supporting plates, a presser foot to engage the work in a way to form a stitching space on all four sides of the presser foot, a rotary member mounted in the central part 100 of the presser foot, a presser foot support 105 connected with said rotary member, and means for operating the presser foot support to shift the relative location of rotary member without changing the position of the latter.

3. A work feeding attachment for sewing machines, comprising a reciprocating slide, a supporting plate attached thereto, a clamping plate having an opening therein, a presser foot adapted to work through the opening 110 of the clamping plate, rotary means for supporting the presser foot, and means for operating the rotary means to change the relative location of the support for the presser foot in a way to allow the sewing machine 115 needle to work all around the presser foot.

4. In a work feeding attachment for sewing machines, the combination of slidable work supporting plates, a presser foot to 120 engage the work, a rotary disk mounted in 125

- the presser foot, a shaft connected with a disk for supporting the presser foot, and means for operating the shaft and disk to shift the point of connection of one with respect to the other.
5. In a work feeding attachment for sewing machines, the combination of work supporting plates, a presser foot to engage the work, an eccentric member for supporting the same, means to raise and lower the eccentric member, and means for moving the said eccentric member with respect to the foot and plates while the sewing machine is in operation.
10. 6. A work feeding attachment for sewing machines, comprising a reciprocating slide, a supporting plate attached thereto, a clamping plate having an opening therein, a presser foot adapted to work through the opening of the clamping plate, yieldable connections for holding the foot in said opening, a rotary supporting means having an eccentric connection with the presser foot to change the relative location of such connection with and lengthwise of the presser foot with each operation of the machine.
15. 7. In a work feeding attachment of the class described, the combination of a reciprocating slide, a supporting plate attached thereto, a clamping plate having an opening therein, an elongated presser foot adapted to work through the opening of the clamping plate, a rocker shaft having an eccentric connection with the presser foot for supporting the same and to move the presser foot connection lengthwise of the presser foot with each operation of the machine.
20. 8. The combination of a reciprocating slide, a supporting plate attached thereto, a clamping plate having an opening therein, means for moving the said slide and connected plates in a rectangular direction, a presser foot also adapted to be moved with the said plates, a rocker shaft for supporting the same and adapted to move with the said plates and presser foot and also independently thereof to change its location of connection of said arm with the presser foot.
25. 9. A work feeding attachment for sewing machines, comprising slidable work supporting plates, a presser foot to engage the work, a rocker shaft having an eccentric pin normally connecting with one end of the presser foot for supporting the same, and means for moving the shaft while the sewing machine is in operation, so as to have the pin connected with a different part of the presser foot at the completion of an operation.
30. 10. In a work feeding attachment for sewing machines, the combination of a slid- able work supporting plate, a presser foot to engage the work, a pin for supporting the presser foot, a shaft upon which the pin is mounted, and means for operating the shaft to move the pin longitudinally with respect to the presser foot while the sewing machine is in operation.
35. 11. In a work feeding attachment for sewing machines, the combination of a reciprocating slide, a supporting plate attached thereto, a hinged plate, a rocker shaft mounted thereon, a clamping plate having an opening therein, a presser foot adapted to work centrally through the opening of the clamping plate, and means carried by the said shaft for engaging the presser foot whereby the relative location of its connection with the foot may be changed with each operation of the machine.
40. 12. In a work feeding attachment for sewing machines, the combination of work supporting plates, a hinged plate connected therewith, a shaft mounted upon the hinged plate and having an extended eccentric member, a presser foot mounted upon the pin to engage the work, means for turning the shaft upon the plate to move the relative point of connection of the eccentric member with respect to the presser foot while the sewing machine is in operation.
45. 13. In an attachment for sewing machines, the combination of a reciprocating slide, a supporting plate attached thereto, a clamping plate also carried by the slide and having an opening therein, a presser foot adapted to work through the opening of the clamping plate, a hinged plate also carried by the slide, a shaft movably mounted on the guide plate, an eccentric connection of the shaft and presser foot to change the relative location of the connection lengthwise of the presser foot with each operation of the machine.
50. 14. In a work feeding attachment for sewing machines, the combination of a reciprocating slide, a guide plate attached thereto, an elongated presser foot, a shaft mounted upon the guide plate and having a relatively movable connection with the presser foot for supporting the same, an arm upon the shaft, means to engage the arm to operate the rocker shaft whereby the presser foot is shifted crosswise with respect to the shaft.
55. 15. In a work feeding attachment for sewing machines, the combination of a reciprocating slide, a guide plate hinged thereto, a clamping plate having an opening therein, means for moving the said slide and connected parts in a rectangular direction, a presser foot also adapted to be moved with the said plates, a rocker shaft mounted on the guide plate for supporting the presser foot, means to hold the shaft in its adjusted position, an eccentric pin carried by the shaft, a rotary disk carried by the presser foot and engaged by the pin to change its location of connection of said pin with the presser foot.
60. 16. In a work feeding attachment for sewing machines, the combination of a reciprocating slide, a guide plate hinged thereto, a clamping plate having an opening therein, means for moving the said slide and connected parts in a rectangular direction, a presser foot also adapted to be moved with the said plates, a rocker shaft mounted on the guide plate for supporting the presser foot, means to hold the shaft in its adjusted position, an eccentric pin carried by the shaft, a rotary disk carried by the presser foot and engaged by the pin to change its location of connection of said pin with the presser foot.

sewing machines, the combination of a reciprocating slide, a guide plate hinged thereto, supporting means for feeding the material to be stitched in a rectangular direction, a presser foot also adapted to be moved with the said guide plates, a guide bracket carried by the guide plate, a rocker shaft mounted in the bracket for supporting the presser foot, collars and springs for holding the shaft in its adjusted position, an eccentric pin carried by the shaft, a rotary disk carried by the presser foot and engaged by the pin to change the location of connection of said pin with the presser foot.

15 17. In a work feeding attachment for sewing machines, the combination of a reciprocating slide, a guide plate hinged thereto, supporting means for feeding the ma-

terial to be stitched, a presser foot also adapted to be moved with the said plates, a 20 movable member carried by the presser foot, a rocker shaft mounted on the guide plate for supporting the presser foot, means to hold the presser foot in its horizontal position, an eccentric member carried by the 25 shaft to engage the movable member to change its location of connection of said eccentric member with the presser foot.

Signed at Bridgeport in the county of Fairfield and State of Connecticut this 20th 30 day of August A. D., 1912.
